US00D588252S

(12) **United States Design Patent**
Conway et al.

(10) **Patent No.:** **US D588,252 S**
(45) **Date of Patent:** **** Mar. 10, 2009**

(54) **REED DIFFUSER AND LIGHT SOURCE**

(75) Inventors: **Simon M. Conway**, Burlington, WI (US); **Stephen Meosky**, Austin, TX (US); **Han Xin**, Austin, TX (US); **Kit R. Morris**, Austin, TX (US)

(73) Assignee: **S. C. Johnson & Son, Inc.**, Racine, WI (US)

(**) Term: **14 Years**

(21) Appl. No.: **29/296,802**

(22) Filed: **Oct. 29, 2007**

(51) **LOC (9) Cl.** **28-99**

(52) **U.S. Cl.** **D23/366; D11/152**

(58) **Field of Classification Search** **D6/403, D6/556; D11/143-156, 164; D19/77, 81, D19/84; D23/355, 366; D26/9, 20, 22; D34/1-11; D99/5, 19; 47/32.7, 39, 41.01, 41.1, 41.12-41.15, 47/65.5, 66.1, 66.6, 66.7, 71**

OTHER PUBLICATIONS

Image of Target brand "Reed Diffuser" ceramic container, with a Universal Product Code of "490540611147" and distributed by Target Corporation, available at least as early as Dec. 31, 2007.

Primary Examiner—Caron D. Veynar
Assistant Examiner—Garth Rademaker

(57) **CLAIM**

The ornamental design for a reed diffuser and light source, as shown and described.

DESCRIPTION

FIG. 1 is a perspective view of a reed diffuser and light source showing our new design;

FIG. 2 is a front elevation view thereof, the rear elevation view being identical thereto;

FIG. 3 is a left side elevation view thereof, the right side elevation view being identical thereto;

FIG. 4 is a top plan view thereof; and,

FIG. 5 is a bottom plan view thereof.
